UNITED STATES PATENT OFFICE.

GILBERT W. GOODRIDGE, OF BRIDGEPORT, CONNECTICUT, ASSIGNEE TO THE BRYANT ELECTRIC COMPANY, OF BRIDGEPORT, CONNECTICUT, A CORPORATION OF CONNECTICUT.

SHADE-HOLDER.

1,065,798.

Specification of Letters Patent. Patented June 24, 1913.

Application filed April 25, 1912. Serial No. 693,200.

To all whom it may concern:

Be it known that I, GILBERT W. GOODRIDGE, a citizen of the United States of America, and residing at Bridgeport, in the county of Fairfield and State of Connecticut, have invented a certain new and Improved Shade-Holder, of which the following is a specification.

My invention relates to shade holders and particularly to that element of the holder by which the shade is secured thereto, the object of my invention being to provide an improved spring device for gripping the usual bead at the upper edge of the shade or globe by which it is customary to support the latter in position.

In the accompanying illustrative drawing, Figure 1 is an elevation partly in vertical section of a shade holder in which my invention is embodied; Fig. 2 is a top plan thereof; Fig. 3 is a partially broken away inverted plan thereof; and Fig. 4 is a perspective of a detail.

The manner of fastening the shade holder on the socket is immaterial. In the example shown, the shade holder body is centrally perforated to permit the passage therethrough of the lamp receiving end of the socket shell 10, the parts abutting at the usual bead 11 on the latter and being united by solder.

The body of the shade holder in the form shown comprises a disk 12, with vertical peripheral skirt 13 and inwardly offset flange 14 at the lower edge of the latter. Within the inwardly faced channel, formed by skirt and flange, I secure a series of short spring bands 15, riveted at 20 to the skirt at one end and projecting inwardly at their free ends to engage the bead of the globe. In order to more effectively accomplish the latter function, the free end of each band is provided with an engaging tongue 16 offset from the end of the band to lie in a substantially radial plane. The lower edge of the tongue 16 is beveled upward to facilitate the adjustment of the globe, while the upper edge is substantially flat or only slightly curved to conform to the curvature of the globe bead. The several springs 15 are normally in their extreme inward position and consequently, since they are of such strength that they cannot be spread by the engagement of the beveled lower edges of the tongues 16, by the globe bead without

danger of fracturing the latter in case it is of glass, I provide each spring 15, with an upwardly projecting arm 17, which passes through a slot 18 in the disk 12 of the holder and is angled above the latter to form a head 19. The latter may be engaged by the finger to push the spring back toward the skirt 13. If desired two or even three of the springs may be thus spread to afford an enlarged space between the tongue 16 to admit the globe bead, upon the insertion of which the springs are released and grip the globe bead by the inwardly pressed tongues 16, as will be readily understood. The weight of the globe is transmitted to the disk 12 of the holder through the heads 19 which span the slots 18; and the rivets 20 are thus relieved from strain. The spring may be made of such width however that it rests upon the inturned flange 14 in which case part of the globe's weight would be transmitted to the latter.

It will be observed that the spring tongues 16 are normally at their extreme inward position and are normally equally pressed toward this position. Consequently, even if but a single spring be retracted during the adjustment of the globe, the release of this spring will result in subjecting the others to equal tension through the transmission of forces by the globe. Consequently the device serves to automatically center the globe in adjusted position. Furthermore, with the exception of the heads 19, the springs are completely concealed within the holder, thus presenting a neat and attractive appearance. Again, owing to the fact that the springs are concealed, they may be made of steel, only the heads 19 being finished to correspond to the body of the holder.

As will be readily recognized, the device is simple to make, while at the same time being effective in its operation.

I claim as my invention:

1. A shade holder having a slotted body portion and a depending peripheral flange thereon, in combination with inwardly projecting spring tongues tangentially mounted on said flange with their free ends normally at their innermost position, one of said tongues having an upwardly extending lug passing through said slotted body-portion of the shade holder and overlying the sides of the slot to form a support and actuating member, for the purpose described.

2. A shade holder comprising a body member with slotted disk top and peripheral depending skirt, a series of spring catches rigidly secured within said skirt with their free ends normally at their innermost position, together with supporting heads on the free ends of said springs passing through the slots in said disk and spanning the latter to support upon the disk the weight of a globe engaged by said spring catches, substantially as described.
3. A shade holder comprising a body member with depending skirt and inturned flange at the lower edge of the latter, in combination with spring catches rigidly secured within said skirt and supported at the lower edges of said flange, substantially as described.
4. A shade holder having a depending peripheral flange, and a series of tangential spring catches each rigidly secured within

the same at one end and having at its free end a globe engaging tongue offset to lie in a substantially radial position, said tongues being normally in their extreme inwardly projecting position.

5. For use in a shade holder of the character described, a spring catch comprising a strip of resilient metal having at one end a globe-bead-engaging tongue offset from the length of the spring and an upwardly extending arm with head adapted to project through a slot in the shade holder body and overlie the metal of the latter, for the purpose described.

In testimony whereof I have signed my name to this specification, in the presence of two subscribing witnesses.

GILBERT W. GOODRIDGE.
